UNITED STATES PATENT OFFICE.

LEONIDAS D. WEST, OF DENVER, COLORADO.

SMOKE-ABATOR.

1,275,339.

Specification of Letters Patent. Patented Aug. 13, 1918.

Application filed December 28, 1917. Serial No. 209,312.

To all whom it may concern:

Be it known that I, LEONIDAS D. WEST, a citizen of the United States, residing at Denver, in the county of Denver and State of Colorado, have invented certain new and useful Improvements in Smoke-Abators; and I do declare the following to be a full, clear, and exact description of the invention, such as will enable others skilled in the art to 10 which it appertains to make and use the same.

My invention relates to improvements in smoke abators of the type which are carried on the inner sides of the coaling doors of 15 furnaces; and one object is to so improve upon the construction of the air heating device as to cause extremely slow passage of air therethrough, so that this air will become highly heated for obtaining the best results 20 as it mixes with the gases within the fire box.

In connection with the air heating device, one or more dampered openings may be employed for admitting additional air for a 25 predetermined time after coaling, this air serving to mix with the gases distilled from the newly supplied coal, so that perfect combustion of all of such gases will take place to prevent smoking and accumulation of 30 soot; and a further object is to provide the air heating device with a plurality of air deflecting webs positioned in the path of the incoming air through said dampered inlets, so that this air is spread over the fire box, 35 thus preventing the gases and air from passing through the combustion chamber unmixed.

A still further object is to so construct the above named webs as to cause them to 40 act as a heat buffer for the door and as a means for relatively bracing said door and the air heating device.

With the foregoing general objects in view, the invention resides in the novel 45 features of construction and unique combinations of parts to be hereinafter fully described and claimed, the descriptive matter being supplemented by the accompanying drawings which form a part of this specification and in which:

Figure 1 is a front elevation of a furnace door equipped with the present invention;

Fig. 2 is a horizontal section on the plane of the line 2--2 of Fig. 1;

Fig. 3 is a vertical section on the plane

indicated approximately on the line 3--3 of Fig. 1;

Fig. 4 is a similar view on the plane of the line 4--4 of Fig. 1; and

Fig. 5 is a horizontal section on the plane 60 of the line 5--5 of Fig. 3.

In the drawings above briefly described, the numeral 1 designates the coaling door of the furnace, said door being of any preferred formation and having upper and 65 lower horizontal air inlet openings 2 which are provided with pivoted dampers 3 linked together for simultaneous operation in the same manner described specifically in my companion U. S. application, Serial No. 70 209,311, filed December 28, 1917. It will here be well, however, to designate the handle of the door by the numeral 4 and to identify the latch for said handle by the character 5. Also, it may be briefly explained that when the handle 4 is raised to open the door 1, it opens the dampers 3 and the latch 5 comes into play to hold them in open position until said latch is tripped either by hand or automatically as is the 80 case with the application above referred to. In either case, the dampers will remain open a sufficient length of time to supply the requisite quantity of fresh air to the fire box immediately after coaling, so that the 85 newly distilled gases will be supplied with sufficient oxygen to render them highly combustible.

Contacting at its front side with the rear face of the door 1, is a hollow preferably 90 rectangular air heating body 6, the ends of said body preferably having angular webs 7 which abut the door as shown clearly in Figs. 2, 3 and 5. One or more tubular air inlets 8 are carried by the front side of the 95 casing 6, said inlets passing through suitable openings in the door and serving as means for securing the heater 6 in place. Suitable apertured caps or the like 9 are provided for the outer ends of the air inlets 8, the apertures of such caps being such as to permit only the proper amount of air to enter, this amount being determined by experiment. It is obvious that the caps 9 may be made in assorted sizes and that caps of the correct characteristics may thus be employed.

The rear side of the hollow body 6 is formed with a pair of tubular bosses 10 which are alined with the air inlets 8; and tubular air retarders 11 pass through said 110

bosses and are formed with open inner ends abutting the casing wall around the inlets 8, the outer ends of said retarders having integral closures 12 preferably flanged for engagement with the bosses as shown. Pins 13 or any other preferred means may be passed through the bosses 10 and through the retarders for holding the latter in place. Each retarder 11 is preferably provided with 5 a plurality of longitudinal air outlet slots 14 which open through its inner end, and also with a suitable number of outlet perforations 15. By this arrangement, the air entering through the apertures of the caps 15, will be more or less trapped in the retarders and slowly expelled from the latter through the several slots and perforations, whereby this air is pre-heated before it is discharged into the main heating casing or 20 body 6. In this casing the air is further heated and is permitted to escape only at a slow rate of speed by the means now to be described.

An air spraying nozzle 16 preferably of 25 the construction shown for directing the air downwardly upon the fire is provided, said nozzle having an integral air inlet neck 17 passing into the body 6 through a central tubular boss 18, the latter being preferably 30 located between the two bosses 10. The inner end of the neck 17 is open and is preferably located adjacent the front wall of the body 6 as shown clearly in Figs. 2 and 4, said neck having a plurality of longitudinal 35 air inlet slots 19 which open through its inner end as shown. A pin or bolt 20 may be passed through the neck 17 and through the boss 18 for holding the nozzle and neck in place, but other suitable attaching means 40 could well be employed should occasion demand. Also, although I have shown and described two air inlets and two retarders, it is obvious that only one of each need be employed in some cases. The same may be 45 said of the dampers 3 although two are preferably employed as shown.

For the purpose of sufficiently spreading the incoming air from the openings 2 over the fire box, a plurality of inclined webs 21 50 are employed, said webs inclining from the inner end portion of the body 6 to the door 1 and extending across the path of the incoming air as will be clear from Figs. 3, 4 and 5. The opposite sides of the webs 21 55 are preferably curved somewhat as seen in Fig. 5 and located at suitable angles to the path of the air to produce best results. These webs are so arranged as to cause them to act as a heat buffer for the door 1, as pre- 60 heating means for the incoming air, as spreading means for this air, and as means for relatively bracing the body 6 and the door 1. The ends of the webs adjacent the body 6 are preferably of greater width as 65 will be clear from Figs. 3 and 4 and

these ends are formed integrally with base bars 22 which contact with the upper and lower sides of body 6 and are formed with integral ears 23. These ears contact with similar ears 24 cast on the body 6 and bolts 70 or the like 25 are passed through the two sets of ears for the purpose of securing the webs 21 rigidly in place.

In operation, the air heating body 6 supplies hot air continuously to the fire box 75 as long as door 1 is closed. This air enters through the caps 9 and inlets 8 and is choked down by the retarders 11, so that it becomes pre-heated. From these retarders, the air slowly enters the casing 6 through the slots 80 14 and perforations 15, and in this casing the air becomes highly heated. The escape of air from casing 6 is further choked down by the neck 17 of the nozzle 16, since it is necessary for the escaping air to pass 85 through the slots 19 and to enter to some extent through the open inner end of said neck, but this end is in such close proximity to the front wall of the casing as to cause the air to impinge upon the latter to insure 90 further heating. As the air leaves the neck 17 and enters the nozzle 16, it suddenly expands and is here even further heated, so that it is discharged from the several perforations of said nozzle in the form of a 95 plurality of jets. These jets of highly heated air thoroughly mix with the gases in the fire box and cause complete combustion of the latter so that smoking and the formation of soot is prevented.

When the door 1 is to be opened for coal-ing, it is necessary to raise the handle 4 and in so doing the two dampers 3 are opened and held in open position by the latch 5. It thus follows that the dampers 100 remain open when the door is again closed, so that a sufficient quantity of fresh air will be supplied to the fire box for insuring proper mixture with the newly distilled gases from the fresh coal. These gases when 105 supplied with sufficient oxygen greatly increase the efficiency of the furnace but it is important that the dampers 3 be closed at the proper time, since the admission of too much air merely chills the fire box. To 110 close the dampers the latch 5 may be released by hand or any preferred automatic release could well be employed, such for instance as that shown in my companion case above referred to.

From the foregoing, taken in connection with the accompanying drawings, it will be obvious that although the several features of my invention are comparatively simple and inexpensive, they will be highly efficient 115 and durable. Since probably the best results are obtained from the details shown, these details are preferably employed, but within the scope of the invention as claimed, numerous minor changes may well be made. 120 125 130

For instance although the nozzle 16 is preferably of sufficient dimensions to shield the inner side of the body 6 against burning out by the heat from the firebox, other 5 shielding means might well be used, and in some cases no such means may be necessary.

I claim:

1. The combination with a furnace coal-ing door having at its inner side an air heater for continuously supplying hot air to the firebox and having adjacent said heater a dampered air inlet for supplying additional air after coaling; of a plurality of webs extending at an angle from said 10 heater to said door and disposed in the path of the incoming air from said inlet.
2. The combination with a furnace coal-ing door having at its inner side an air heater for continuously supplying hot air to the fire box and having adjacent said 15 heater a dampered air inlet for supplying additional air after coaling; of a plurality of webs extending at an angle from said heater to said door and disposed in the path of the incoming air from said inlet, the sides of said webs being disposed at 20 angles to the path of the incoming air to spread such air over the fire box,
3. The combination with a furnace door having upper and lower dampered air inlet openings and an air heater between 25 said openings for continuously supplying hot air to the fire box; of a plurality of webs extending at an angle from said heater to said door and substantially spanning 30 said openings, the sides of said webs being disposed at angles to the paths of the incoming air to spread such air over the fire box.
4. A structure as specified in claim 3, together with a base bar to which one end of 35 said webs is secured and means for securing said base bar to said heater.
5. A structure as specified in claim 3, together with a base bar to which one end of 40 said webs is secured, said base bar having an integral ear, an additional ear on said heater with which said first named ear contacts, and a bolt passing through the two ears.
6. An air heater for furnaces comprising 45 a hollow body having in its front side an air inlet opening and in its rear side an opening alined with said inlet opening, a tubular air retarder passing through said last named opening and having an open front 50 end abutting the front side of said body around said inlet opening, said retarder having restricted air outlet openings, a closure for and carried by the rear end of 55 said retarder, and means for securing said retarder in place, said body having a hot air outlet.
7. An air heater for furnaces comprising a hollow body having in its front side an air inlet opening and in its rear side an additional opening, an apertured air retarder in 60 said body receiving the air from said inlet opening, and an air spray nozzle having a tubular apertured neck extending into 65 said body through the opening in the rear side thereof.
8. An article of manufacture comprising a metal bar having a flat side adapted to bear against an air heating device on the interior of a furnace, said bar having a lateral 70 apertured ear for securing it in place, and a plurality of webs joined at one end to said bar and spaced apart along the same, said webs extending at an angle to the aforesaid flat side of the bar and being 75 adapted to span an air inlet of the furnace.
9. An article of manufacture comprising an air spraying head having a reduced air inlet neck open at its free end, said neck having longitudinally disposed air inlet 80 slots which open through said open end of the neck.
10. An air heater for furnaces comprising an air heating casing heated by exposure to the heat from the firebox and having 85 an inner end wall provided with an air outlet, and an air outlet nozzle communicating with said casing and located between said inner end wall thereof and the fire, the area of said nozzle on the side thereof adjacent 90 said end wall being substantially equal to the area of said wall, whereby to shield the latter against the fire.

In testimony whereof I have hereunto set my hand.

LEONIDAS D. WEST.
